(57) **CLAIM**

The ornamental design for a table, as shown and described.

DESCRIPTION

FIG. 1 is a perspective view of a first embodiment of a table showing my new design;

FIG. 2 is a front elevational view of FIG. 1;

FIG. 3 is a rear elevational view of FIG. 1;

FIG. 4 is a left elevational view of FIG. 1;

FIG. 5 is a right elevational view of FIG. 1;

FIG. 6 is a top plan view of FIG. 1;

FIG. 7 is a bottom plan view of FIG. 1;

FIG. 8 is a perspective view of a second embodiment of a table showing my new design;

FIG. 9 is a front elevational view of FIG. 8;

FIG. 10 is a rear elevational view of FIG. 8;

FIG. 11 is a left elevational view of FIG. 8;

FIG. 12 is a right elevational view of FIG. 8;

FIG. 13 is a top plan view of FIG. 8;

FIG. 14 is a bottom plan view of FIG. 8;

FIG. 15 is a perspective view of a third embodiment of a table showing my new design;

FIG. 16 is a front elevational view of FIG. 15;

FIG. 17 is a rear elevational view of FIG. 15;

FIG. 18 is a left elevational view of FIG. 15;

FIG. 19 is a right elevational view of FIG. 15;

FIG. 20 is a top plan view of FIG. 15;

FIG. 21 is a bottom plan view of FIG. 15;

FIG. 22 is a perspective view of a fourth embodiment of a table showing my new design;

FIG. 23 is a front elevational view of FIG. 22;

FIG. 24 is a rear elevational view of FIG. 22;

FIG. 25 is a left elevational view of FIG. 22;

FIG. 26 is a right elevational view of FIG. 22;

FIG. 27 is a top plan view of FIG. 22;

FIG. 28 is a bottom plan view of FIG. 22;

FIG. 29 is a perspective view of a fifth embodiment of a table showing my new design;

FIG. 30 is a front elevational view of FIG. 29;

FIG. 31 is a rear elevational view of FIG. 29;

FIG. 32 is a left elevational view of FIG. 29;

FIG. 33 is a right elevational view of FIG. 29;

FIG. 34 is a top plan view of FIG. 29;

(Continued)

FIG. 35 is a bottom plan view of FIG. 29;
FIG. 36 is a perspective view of a sixth embodiment of a table showing my new design;
FIG. 37 is a front elevational view of FIG. 36;
FIG. 38 is a rear elevational view of FIG. 36;
FIG. 39 is a left elevational view of FIG. 36;
FIG. 40 is a right elevational view of FIG. 36;
FIG. 41 is a top plan view of FIG. 36; and,
FIG. 42 is a bottom plan view of FIG. 36.

The broken lines shown in the drawings are included for the purpose of illustrating elements of the table that form no part of the claimed design.

The drawings include a symbolic break in its length. The appearance of any portion of between the break lines forms no part of the claimed design.

The shading in FIGS. 15-42 is included to depict an ombre base that transitions from a darker to lighter coloration in a direction towards the table top.

1 Claim, 36 Drawing Sheets
